AUTOMATIC BOILER WATER CONDITIONER

Lewis O. Gunderson and Oland W. Carrick,
 Chicago, Ill., assignors to Electro-Chemical
 Engineering Corporation, Chicago, Ill., a cor-
 poration of Delaware

Application December 24, 1937, Serial No. 181,490

18 Claims. (Cl. 122—389)

This invention relates to the automatic removal from operating steam boilers of foam and foam forming ingredients without discharge of relatively good boiler water therewith.

More specifically the invention relates to the collection of light water and foam developed throughout and above the steam generating zone of the boiler during operation of the boiler which collected material is periodically discharged from the boiler whenever steam and liquid conditions in a valve mounted on the boiler are varied from a predetermined condition.

This application is a continuation-in-part of the Carrick and Gunderson application entitled: "Automatic boiler water conditioner and blow-off system," U. S. Serial 104,760, filed October 9, 1936, now Patent No. 2,132,028, granted October 4, 1938.

In the operation of steam boilers, it is desirable to maintain a substantially constant level for the boiler water. For this purpose, sight glasses are usually provided on steam boilers to indicate the water level in the boiler. However, when the steam boiler is in operation and supplying steam, a mass of steam expanded or light water is formed throughout the steam generating zone of the main body of boiler water. Foam may also be formed on top of the boiler water or light boiler water. Since the foam and light boiler water is composed of a myriad of steam bubbles and has less density than the boiler water, the actual upper level of foam or light water is not indicated in the sight glass.

At times during the operation of a steam boiler, the entire steam space may be filled with foam or light water. These materials, under such conditions, of course are delivered from the boiler with the steam. The boiler then supplies a low quality steam.

We have found that foam forming and foam stabilizing ingredients in boiler water accumulate or are adsorbed in the steam bubble interfaces of the light boiler water and in the foam film. As these substances are released at the surface of the light boiler water upon breaking of the steam bubbles, they are free to recirculate in the boiler water and repeat their function of bringing about foam formation and foam stabilization by being again adsorbed in the surfaces of new steam bubbles formed in the evaporation zone of the boiler.

According to one embodiment of this invention, a collecting means is positioned in the upper portion of a boiler above the normal water level maintained therein but having the inlet

thereof below a level considered dangerous for the foam and light water. In other words, the inlet of the collecting means is within the zone reached by a safe development of foam or light water formed during a working of the boiler. Thus these materials, having the foam forming and foam stabilizing ingredients concentrated therein, are collected in the collecting means before they reach a level in the boiler sufficiently high to be entrained with the steam issuing from the boiler.

The collecting means is allowed to accumulate a predetermined amount of the foam and light water therein and the collected material is then automatically blown out of the boiler at intervals.

In another embodiment of the invention, the collecting means are dispensed with. A down pipe extends down into the boiler and terminates above the normal water level therein but below a level considered dangerous for foam formation. Valve means are associated with the down pipe to effect automatic discharge of foam and light water whenever the down pipe is submerged in these materials.

For the purpose of effecting an automatic removal of the foam and light water from the boiler, a discharge valve is mounted preferably on top of the boiler. This valve receives a down pipe communicating with the lower portion of the collecting means or the down pipe described above terminating within the foam or light water zone of the boiler.

The valve is provided with one or more piston operated auxiliary valves having the pistons thereof subjected to boiler pressure. Vents or bleeder passageways are provided for releasing the boiler pressure from the pistons to allow the boiler pressure acting on the valves to hold the valves closed. Pilot valves are provided to open and close the bleeder passageways or vents. These pilot valves are actuated by the entrance of liquid into the valve for either raising a float in the valve or for changing the temperature of the steam passing through the bleeder passageways or vents. When liquid enters the valve the auxiliary valves are opened to permit the boiler pressure to blow the foam or light water out of the boiler.

If desired, duplex valves can be used having a pair of piston operated auxiliary valves therein for blowing down the mud ring of the boiler simultaneously with the discharge of foam or light water or for increasing the rate of discharge of the foam or light water by providing two outlets therefor.

It is then an object of this invention to automatically discharge foam and light water from an operating steam boiler whenever liquid enters a valve mounted on top of the boiler.

5 A further object of this invention is to discharge foam and light water from an operating steam boiler at a level above the normal water level in the boiler by venting the steam space of the boiler with the atmosphere through a 10 down pipe terminating in the boiler within the foam zone until the mouth of the down pipe is submerged in foam or light water and utilizing the liquid entering the down pipe to effect a blowing off of the foam and light water in the 15 boiler.

Another object of this invention is to provide a thermally operated discharge valve for automatically effecting periodic discharge of foam from the boiler.

20 A further object of this invention is to collect foam forming and foam stabilizing ingredients in the upper portion of an operating steam boiler and to provide a valve on top of the boiler adapted to be opened by an entrance of liquid 25 therein from the collecting means for removing the collected material from the boiler.

Another object is to provide apparatus for automatically blowing down a desired portion of the boiler before light water development in the 30 boiler reaches a dangerous level.

Other and further objects of this invention will become apparent to those skilled in the art from the following detailed description of the annexed sheets of drawings which disclose preferred embodiments of the invention.

35 While the invention illustrated on the drawings is applied to a locomotive boiler, it should be understood that any type of steam boiler can be benefited by the apparatus of this invention. The appended claims are therefore intended to cover the use of the apparatus of this invention on any type of steam boiler.

On the drawings:

Figure 1 is a fragmentary diagrammatic side 45 elevational view of a locomotive, with a part broken away and shown in vertical cross section, to illustrate an embodiment of this invention operatively mounted on the locomotive.

Figure 1A is a view similar to Figure 1 but 50 illustrating a modification wherein the lower portion of the boiler is also blown down.

Figure 2 is a fragmentary side elevational view of a locomotive, with a part broken away and shown in vertical cross section to illustrate an- 55 other modification of this invention.

Figure 3 is a vertical cross-sectional view of a thermally operated valve and attendant mechanism forming part of the apparatus of this invention, mounted on a locomotive boiler shell also 60 shown in cross section.

Figure 3A is a diagrammatic view of a blow off valve that can be actuated by the thermally operated valve shown in Figure 3.

Figure 4 is an enlarged vertical cross-sectional 65 view of a liquid operated valve forming part of the apparatus of this invention.

Figure 5 is a vertical cross-sectional view of another form of liquid operated valve forming part of the apparatus of this invention.

70 As shown on the drawings:

In Figure 1 the reference numeral 10 designates generally a locomotive comprising the usual boiler shell 11, fire box 12 and engineer's cab 13. The fire box 12 is defined by front and rear sheets 75 14 and 15 and a crown sheet 16.

The reference numeral 17 designates the level of water in the boiler as indicated in conventional sight glass. The top level of this boiler water is usually maintained about at least 3 to 5 inches above the crown sheet 16.

5 The space 18 at the top of the boiler is the steam space from which steam is supplied to the steam dome 19 for delivery through the throttle pipe 20 to the operating cylinders (not shown) of the locomotive.

10 During the operation of the boiler, light water or foam 21 is formed throughout and above the steam generating zone of the boiler. This light water or foam is of materially less density than the boiler water, since it is composed of a myriad of steam bubbles. The top level of the light water or foam 21 in the boiler is not indicated by the usual sight glass provided in the engineer's cab because of the lower density of this material. As a result, the engineer usually has no indication of the level of the foam or light water in the boiler. This material can therefore fill the entire steam space 18 without knowledge of the engineer and will be entrained in the steam entering the dome 19 for delivery to the operating cylinders. Obviously, since such moisture entrainment is not desirable, the foam level or light water level in the boiler should be maintained as low as possible to prevent moisture entrainment 15 in the steam.

20 According to this invention, an open topped pan 22 is mounted in the boiler 11 and has the top edges thereof below a level considered dangerous for foam or light water. The pan 22 is suspended from the top of the boiler 11 on straps 25 23.

25 The pan 22 can thus receive light water or foam 21 therein together with the accumulated adsorbed foam producing and foam stabilizing foreign matter.

30 The pan 22 is preferably mounted immediately behind the steam dome 19 to intercept foam or light water that might otherwise pass into the steam dome.

35 According to the modification of the invention shown in Figure 1, a valve 25 is mounted on top of the boiler shell 11. The valve 25 includes a lower chamber 26 having an inlet 27 giving entrance thereto. A float 28 is movably mounted in the chamber 26. The valve 25 also has a top 50 chamber 29 provided with an inlet 30 giving entrance thereto.

40 A third chamber 31 is provided between the chambers 26 and 29. The chamber 31 has a discharge port 32.

45 A pipe 33 extends from the inlet port 27 of the valve, through the boiler shell 11 and into the lower portion of the pan 22. When liquid is collected in the pan 22 the boiler pressure within the boiler 11 will raise the liquid through the pipe 33 into the chamber 26 for raising the float 28 to open the valve.

50 A second pipe 34 extends from the inlet port 30 of the chamber 29 through the boiler shell 11 into the bottom portion of the pan 22. When the valve 25 is opened by liquid entering the chamber 26, the material collected in the pan 22 will be blown up through the pipes 33 and 34 into the valve 25 and out of the discharge port 32 thereof. A pipe 35 is fitted into the discharge 55 port for receiving the material issuing from the valve and for feeding this material into a steam separator 36 mounted on top of the boiler shell 11 in front of the engineer's cab 13. The steam separator 36 is of known construction and has a 60 70 75 75

steam outlet 37 extending upwardly therefrom and a liquid drain line 38 extending to the bottom of the locomotive.

Steam flashed from the liquid supplied to the steam separator 36 is thus vented to the atmosphere while the hot liquid can drain with harmless force, through the drain pipe 38, to the road bed beneath the locomotive.

The pipes 33 and 34 provide for a rapid emptying of the pan 22. However, as will be herein-after more fully described, the valve 25 is not opened until the lower ends of the pipes 33 and 34 are submerged in liquid collected in the pan. In this manner, appreciable amounts of steam 15 cannot be wasted from the boiler.

If desired, instead of utilizing the pipe 34 to increase the rate of discharge from the pan 22 as shown in Figure 1, a pipe 34', shown in Figure 1A, can be fitted into the inlet port 30 of the valve 25 in place of the pipe 34. In Figure 1A parts identical with parts shown in Figure 1 have been designated by the same reference numerals. The pipe 34' communicates with the lower portion of the boiler as at 39 for blowing 25 off sludge from the bottom of the boiler whenever the valve 25 is opened. A control valve 39' can be provided in the pipe line 39 for regulating the amount of blow-off. The pipe 34' therefore makes possible a simultaneous blowing down 30 of the lower portion of the boiler with the emptying of the pan 22.

As best shown in Figure 4, the valve 25 has an open ended cylinder 40 in the chamber 31 thereof. Pistons 41 and 42 are slideable in the cylinder 40. The stem 43 of a poppet valve 44 is secured to the piston 41 while the stem 45 of another poppet valve 46 is secured to the piston 42.

The valve 44 seats on a valve seat 47 disposed 40 between the chambers 26 and 31 of the valve. A second valve seat 48 receives the poppet valve 46 thereon. The seat 48 is mounted between the chambers 29 and 31 of the valve.

When the valves 44 and 46 are in full seating 45 relation on the valve seats 47 and 48 a space 49 is provided between the pistons 41 and 42 in the cylinder 40. This space 49 communicates through a passageway 50 formed through the valve stem 43 and the valve 44 with the chamber 26 of the 50 valve.

A bleeder passageway 51 is formed through the piston 42 and valve stem 45 joining the space 49 with the chamber 31. The mouth of the bleeder passageway 51 is beveled as at 52 to provide a 55 seat for a small pilot valve 53 secured on the end of a rod 54 extending through the passageway 50 into the chamber 26 and attached to the float 28 in the chamber.

The float 28 is a closed annular container having an axial passageway 55 through the center thereof.

A tube 56 is threaded into the valve seat 47 and extends into the passageway 55. The tube 56 carries bushings 57 for slidably receiving the 65 rod 54. Passageways 58 are formed through the bushing supporting portions of the tube to permit passage of fluid from the chamber 26 up through the tube and through the passageway 50 into the space 49 between the pistons.

70 When the float 28 is resting at the bottom of the chamber 26, the pilot valve 53 is unseated from its seat 52 and the chamber 26 is thus in communication through the passageway 50, space 49 and passageway 51, with the discharge chamber 31. Under such conditions, boiler pressure

acting against the valves 44 and 46 will maintain the valves seated on their valve seats. Steam entering the space 49 between the pistons from the chamber 26 by virtue of the pipe connection 33 with the interior of the boiler is led through the passageway 51 into the discharge chamber. Pressure in the space 49 between the pistons can therefore not build up to a degree sufficient to overcome the boiler pressure applied to the valves 44 and 46. However, when the mouth of the pipe 33 is submerged in liquid in the pan 22, liquid will be blown by the boiler pressure into the chamber 26 causing the float 28 to rise in the chamber and seat the pilot valve 53 on its seat 52. The space 49 is thus sealed and boiler pressure existing in the chamber 26 will be applied to the space 49 through the passageway 50. As shown, the top portion of the rod 54 is in spaced relation from the walls defining the passageway 50.

As the pressure in the space 49 builds up, the 20 pistons 41 and 42 are forced toward the ends of the cylinder 40 to open the valves 44 and 46. Liquid will thus be blown from the boiler through the pipes 33 and 34 or 34' into the chambers 26 and 29 of the valve 25. Since these chambers are 25 in direct communication with the discharge chamber 31, the liquid will be blown out of the valve through the pipe 35.

When the liquid level in the pan 22 in the boiler subsides below the mouth of the pipe 33, 30 only steam will be supplied to the chamber 26 of the valve and the liquid in the chamber will be rapidly discharged through the open valve 44 thus permitting the float 28 to again sink to the bottom of the chamber. The space 49 between 35 the pistons will then be vented to atmospheric pressure and the boiler pressure on the valves 44 and 46 will rapidly close these valves.

From the above description it should be understood that a small amount of steam is bled from 40 the boiler through the valve 25 until liquid enters the chamber 26 of the valve through the pipe 33. When such condition arises the valve will be opened to permit a rapid discharge of the material collected in the pan 22 through the pipes 45 33 and 34, or, if desired, through only one pipe while another pipe 34' can be used to blow down the lower portion of the boiler.

Since the valve 25 can only open when the mouth of the pipe 33 is submerged in liquid collected in the pan 22 there is no appreciable wasting of steam. The small amount of steam bled through the passageway 51 of the valve does not represent a measurable loss. Since the pan 22 can only collect contaminated light water or 55 foam formed on top of the relatively good boiler water, this better boiler water likewise cannot be wasted from the boiler.

The device is entirely automatic in operation and serves to maintain the foam and light water 60 in a boiler below a dangerous level. Since the foam forming and foam stabilizing ingredients are concentrated in the foam and light water, the removal of these materials from the boiler decreases the production of foam and eventually eliminates the foaming tendencies of the boiler water.

In the modification of the invention shown in Figures 2 and 5, parts identical with the parts described in Figures 1 and 4 have been marked 70 with the same reference numerals. In this modification the collecting pan 22 may be dispensed with and only a single acting valve 60 is provided. The valve 60 contains only the bottom auxiliary valve or poppet valve 44 and piston 41 75

of the valve 25. The down pipe 33, instead of terminating in a collecting means, extends directly into the steam space of the boiler and terminates above the normal water level but below the level considered dangerous for foam or light water development.

The valve 60 utilizes the same lower housing member defining the chamber 26; the same float 28, and attendant auxiliary and pilot valve constructions as are used in the valve 25. However the valve 60, as best shown in Figure 5, does not have the upper inlet compartment and attendant auxiliary valve constructions of the valve 25. As shown in Figure 5, the valve 60 has an upper housing member 61 providing a discharge chamber 62 with the discharge port 32 therein receiving the end of the pipe 35.

A cylinder 63 is formed in the discharge chamber 62 of the housing 61 and has an open bottom end in alignment with the valve seat 47. The piston 41 slides in the cylinder 63.

The top end of the cylinder 63 is closed by the top of the housing 61 and thus provides a space 64 above the piston 41. A small bleeder passageway 65 is formed through the top of the housing 61 communicating with the space 64. The mouth of the passageway 65 has a valve seat 66 for receiving the pilot valve 53.

When the end of the pipe 33 is not submerged in foam or light water in the boiler, steam will enter the pipe and pass through the chamber 26 of the valve into the space 64 above the piston. When the float 25 is not raised by liquid in the chamber 26, the pilot valve 53 will be spaced from the valve seat 66 and the steam entering the space 64 can bleed out of the valve 60 through the passageway 65. Under such conditions the auxiliary valve 44 will be subjected to boiler pressure while the space above its operating piston 41 will be vented to the atmosphere. The valve 44 will thus remain closed.

However when foam or light water surrounds the mouth of the pipe 33, pressure within the boiler 11 will blow this liquid into the chamber 26 of the valve thereby causing the float 28 to rise and effecting a seating of the pilot valve against its seat 66. The space 64 will then be sealed from the atmosphere and will be subjected to boiler pressure existing in the chamber 26, since this space is in communication with the chamber through the passageway 50. The piston 41, under such conditions, will be forced toward the end of the cylinder 63 to open valve 44. The foam and light water will then be rapidly blown through the pipe 33 into the chamber 26 and up through the tube 56 past the open valve 44 into the discharge chamber 43 from which it is drained through the pipe 35. The valve will remain open as long as sufficient liquid is supplied to the chamber 26 to raise the float 28. However, when the liquid level in the boiler subsides beneath the mouth of the pipe 33, only steam will be supplied to the chamber 26 and the float will drop to again vent the space 64 to the atmosphere and allow the valve 44 to close.

In this modification of the invention, therefore, only a negligible amount of steam is vented to the atmosphere when the valve 60 is in closed position. When the valve 60 is opened, the steam vent is sealed and foam or light water in the boiler is rapidly discharged out of the boiler. Since the valve 60 cannot open unless the mouth of the pipe 33 is submerged in liquid, appreciable amounts of steam cannot be wasted.

In the modification of the invention shown in

Figure 3, parts identical with the parts described in Figures 1, 2, 4 and 5 have been marked with the same reference numerals. In this modification of the invention a thermal operating valve 70 is mounted on top of the boiler shell 11. The valve 70 comprises a housing 71 having an inlet port 72 threaded through the boiler shell 11 and receiving therein a down pipe 73 extending into the lower portion of the collecting pan 22. A valve seat 74 is also threaded into the inlet for receiving a poppet type auxiliary valve 75.

The housing 71 defines a chamber 76 having an outlet port 77 receiving the end of the discharge pipe such as 35.

A cylinder 78 is formed in the chamber 76 and has an open bottom end in alignment with the inlet port 72.

A piston 79 formed integrally with the poppet valve 75 is slidable in the cylinder 78. The top 20 of the housing 71 closes the other end of the cylinder and a space 80 is provided above the piston 79.

A passageway 81 is formed through the valve 75 and piston 79 joining the interior of the pipe 25 73 with the space 80.

A small bleeder passageway 82 is formed through the top of the housing 71 joining the space 80 with a chamber 83 formed by a secondary housing member 84 on top of the housing 30 member 71. The chamber 83 has a discharge port 85 receiving the end of a drain tube 86 therein.

A large bleeder passageway 87 is also formed through the top of the housing 71 joining the space 80 with the chamber 83.

A small pilot valve 88 is mounted in the chamber 83 on a bimetal concave Spencer disc 89. The disc 89 is supported at its periphery by supports such as 90 formed in the chamber 83.

As is known, bimetal Spencer discs are sensitive to temperature changes and the disc 89 is formed so that a drop in temperature in the chamber 83 will move the disc so as to pull the pilot valve 88 away from the bleeder passageway 45 87.

When the mouth of the down pipe 73 is not submerged in foam or light water, steam will bleed from the space 80 above the piston 79 through the small bleeder passageway 82 where 50 it is released to atmospheric pressure in the open chamber 83. This open chamber allows the steam to expand and, when dry steam is thus discharged through the orifice 82, a superheating occurs raising the temperature surrounding 55 the disc 89 materially above 212° F. Under such heated conditions the disc 89 is expanded to force the pilot valve 88 against the mouth of the passageway 87.

The passageway 82 is sufficiently small so that 60 the space 80 is maintained under pressure as long as the passageway 87 is closed by the pilot valve 88. This pressure will act directly against the top of the piston 79 to hold the valve 75 against its seat 74. The interior of the pipe 73 will then 65 not communicate with the discharge chamber 76.

However, when the mouth of the pipe 73 is submerged in liquid collected in the pan 22, moisture will necessarily be entrained with the steam entering the space 80 above the piston. If 4% 70 or more of moisture or water is discharged with the steam through the orifice 82 into the chamber 83, the temperature in the chamber will be reduced to 212° F. Under such conditions, the Spencer disc 89 will contract upwardly to pull 75

the pilot valve away from the passageway 87 and this passageway will be vented to the atmosphere.

The combined rate of bleeding through the 5 passageways 82 and 87 reduces the pressure in the space 80 sufficiently to allow the boiler pressure acting on the valve 75 to unseat this valve. The pipe 73 will thus communicate with the discharge chamber 76 and material collected in the 10 pan 22 will be blown through the valve 70 out of the boiler. As soon as the mouth of the pipe 73 is uncovered, however, dry steam will be bled through the orifices 82 and 87 to raise the temperature in the chamber 83 and cause the disc 15 to again seat the pilot valve 88. Pressure in the space 80 will again build up to an amount sufficient to reseat the valve 75.

In this modification of the invention, therefore, only small amounts of steam are vented 20 to the atmosphere, and, when the quality of the steam vented to the atmosphere is lowered to a point where it carries approximately 4% or more of moisture, the valve 70 will be opened to permit discharge of foam and light water from the 25 boiler.

It should be understood that other thermal operating means for actuating the pilot valve 88 can be used in place of a Spencer disc. For example, a "Sylphon" type bellows can be used.

30 Instead of discharging from the valve 70 into the steam separator the pipe 35 may be connected to the inlet 100 of a remote blow off valve 101 shown in Figure 3A.

The blow off valve 101 comprises a casing 102 35 having the inlet 100 at the top thereof and a second inlet 103 at the bottom thereof. The inlet 103 receives the end of a pipe 104 communicating with the interior of the boiler at any desired level therein such as for example at the 40 bottom of the mud ring.

The casing 102 defines a bottom 105 having the inlet 103 and a top chamber 106 having the inlet 100. An outlet 107 is provided for the chamber 106 through the side wall of the casing. 45 The outlet 107 may receive a pipe 108 leading to a steam separator such as the separator 36.

An open ended cylinder 109 is formed in the chamber 106 below the inlet 100. The top of the cylinder is spaced below the inlet 100 so as to 50 place the inlet in restricted communication with the outlet 107.

An opening 110 joins the chambers 106 and 105 and a valve seat 110a is formed around the bottom end of the opening. A valve 111 is adapted to seat on the valve seat 110a for closing the 55 opening.

The valve 111 has a stem 112 extending into the cylinder 109 and a piston 113, slidably in the cylinder, is secured to the end of this stem.

60 Boiler pressure in the pipe 104 will normally hold the valve 111 against the seat 110a to close the blow off valve 101. However, when the valve 70 is open, boiler pressure acts, through the pipe 35, on the piston 113 to slide the same toward the opening 110 and thereby unseat the valve 111. The blow off valve 101 is thus opened and the boiler will be blown down.

Liquid from the pipes 35 and 104 will be discharged through the outlet 107.

70 It should be understood that the area of the top of the piston is much greater than the area of the bottom of the valve 111 and that the inlet 100 is only in restricted communication with the outlet 107 so that the boiler pressure acting 75 on the large piston area will slide the piston

against the boiler pressure acting on the small valve area.

In this modification therefore the pilot valve operates a remote blow off valve for blowing down any desired portion of the boiler.

The collecting pan 22 shown in Figure 3 may be dispensed with, if desired, and the valve 70 will then operate by direct communication with the steam space of the boiler as does the valve 60 described in Figure 2. Likewise, the double 10 acting or duplex valve described in Figure 1 can be used without a collecting pan or the single acting valve described in Figure 2 can be used with a collecting pan.

In all modifications of this invention, therefore, the entrance of liquid into a valve effects an opening of the valve to discharge from the boiler, light water and foam containing foam stabilizing and foam forming ingredients and/or boiler water from any desired portion of the 20 boiler.

We are aware that many changes may be made and numerous details of construction may be varied through a wide range without departing from the principles of this invention, and 25 we, therefore, do not purpose limiting the patent granted hereon otherwise than necessitated by the prior art.

We claim as our invention:

1. In apparatus for controlling foaming in operating steam boilers including collecting means mounted in the upper portion of the boiler and having an inlet above the normal water level in the boiler but below the steam outlet of the boiler, a valve housing mounted outside of said boiler, and a tube joining the interior of the valve housing with the bottom portion of the collecting means, the improvements which comprise a piston slidable in said valve housing, a valve connected to said piston in such a manner 30 so as to be opened by the piston when one side thereof is subjected to boiler pressure, said valve and piston having a bleeder passageway there-through communicating said side of the piston with the boiler pressure, means venting said side of the piston to the atmosphere, a pilot valve 35 for closing the vent and means responsive to liquid entering the valve housing for actuating the pilot valve whereby boiler pressure is allowed to build up against the piston for opening the valve to permit discharge of material from the collecting means.

2. In apparatus for removing foam forming and foam stabilizing ingredients from operating steam boilers including a collecting means mounted in the upper portion of a boiler having an inlet above the normal water level in the boiler but within the zone reached by a safe development of foam on top of the boiler water, the improvements which comprise a valve housing 55 mounted on top of the boiler having an inlet compartment and an outlet compartment, a tube extending from said inlet compartment of the valve housing downwardly into spaced relation from the bottom of the collecting means, a poppet valve in said valve housing separating the inlet and discharge compartments, a piston secured to said poppet valve in such a manner to open the valve when one side of the piston is subjected to boiler pressure, a bleeder passageway extending through said piston and poppet valve for joining the inlet and discharge compartments, a cylinder for slidably receiving said piston, means defining a bleeder passageway for venting the space in the cylinder above the piston to the 60 65 70 75

atmosphere, a float in said inlet chamber, a rod carried by said float extending through the bleeder passageway into the space above the piston, a pilot valve seated on the end of said rod for closing the vent passageway and a guiding tube surrounding said rod in the inlet chamber and extending into spaced relation from the bottom of the chamber whereby an entry of liquid into the inlet chamber will cause the float 10 to rise and seat the pilot valve against the mouth of the vent passageway and boiler pressure will be exerted against said side of the piston to open the poppet valve for discharge of liquid into the discharge chamber up through the guiding tube.

15 3. In apparatus for controlling foaming in operating steam boilers including a collecting means mounted in the upper portion of the boiler having an inlet above the normal water level in the boiler but below the steam outlet of the boiler, the improvements which comprise a valve housing mounted on top of the boiler having top and bottom inlet compartments and an intermediate discharge compartment between the inlet compartments, auxiliary valves in said valve housing 20 joining the inlet compartments with the discharge compartment, an open-ended cylinder in said discharge compartment, pistons slideable in said cylinder secured to said auxiliary valves in such a manner as to open said valves when said pistons 25 are subjected to boiler pressure, said valve between the lower inlet compartment and the discharge compartment having a passageway joining the inlet compartment with the space in the cylinder between the pistons, said other auxiliary 30 valve having a bleeder passageway joining said space with the discharge compartment, a float mounted in said bottom inlet compartment, a rod secured to said float and extending through the passageway of the auxiliary valve, a pilot valve 35 carried on the end of said rod in the space between the pistons adapted to seat against the mouth of the bleeder passageway, a pipe extending from the bottom inlet compartment downwardly into the lower portion of the collecting 40 means, and a pipe line extending from said top inlet compartment into the boiler, whereby steam will be vented from the boiler through the valve housing only until the pipe communicating with the bottom inlet compartment is submerged in 45 liquid whereupon said liquid will enter said compartment to raise the float and seat the pilot valve against the mouth of the bleeder passageway whereupon boiler pressure will build up in the space between the pistons to open the auxiliary valves for emptying the material collected 50 in the collecting means.

4. In apparatus for controlling foaming in operating steam boilers which comprises a collecting means mounted in the upper portion of a boiler having an inlet above the normal water level therein but below a dangerous foam level, the improvements which comprise a valve housing mounted on top of the boiler having top and bottom inlet compartments and an intermediate discharge compartment, piston operated auxiliary valves in said valve housing separating the inlet compartments from the discharge compartment and arranged to be opened when the pistons are subjected to boiler pressure, an open-ended cylinder in said discharge compartment receiving the pistons of the auxiliary valves in slideable relation therein, means venting the space in the cylinder between the pistons with the atmosphere, means joining the space in the cylinder 55 between the pistons with the bottom inlet com-

partment, a float in said bottom inlet compartment, a rod secured to said float and extending into the space between the pistons, a pilot valve on the end of said rod controlled by said float to open and close the vent means, and down pipes joining the inlet compartments with the lower portion of the collecting means, said float being arranged to move the pilot valve to closed position only when raised by liquids from the boiler, whereby steam from the boiler will be 10 vented through the valve housing until the down pipe communicating with the bottom inlet compartment of the housing is submerged in collected liquid whereupon said liquid will raise the float to actuate the pilot valve for closing the 15 vent passageway and sealing the space between the pistons from the atmosphere to allow boiler pressure to open the auxiliary valves and rapidly discharge the collected material from the collecting means into the discharge compartment of 20 the valve.

5. In apparatus for controlling foaming in operating steam boilers including a collecting means mounted in the upper portion of the boiler having an inlet above the normal water level in the boiler but below the steam outlet of the boiler, the improvements which comprise a valve housing mounted outside of the boiler having two inlet compartments and a discharge compartment, piston operated auxiliary valves separating the inlet compartments from the discharge compartment and arranged to be opened by pressure differentials on opposite sides thereof, a pilot valve controlling said pressure differentials by periodically venting one side of the valves to 35 the atmosphere, a float in one of the inlet compartments for actuating the pilot valve, a pipe extending from the inlet compartment having the float therein into the bottom portion of the collecting means, a second pipe extending from 40 the other inlet compartment into communication with the lower portion of the boiler, said float and pilot valve being so arranged as to so control said pressure differentials that the auxiliary valves open upon a predetermined movement of the float whereupon an entry of liquid into the inlet compartment from the collecting means will move the float and the pilot valve to open the auxiliary valves and material collected in the collecting means will be blown out 45 of the boiler simultaneously with sludge water from the lower portion of the boiler.

6. Apparatus for removing foam forming and foam stabilizing ingredients from operating steam boilers which comprises a valve housing mounted 55 on top of a boiler, a tube extending downwardly from said valve housing into the boiler, the mouth of said tube being above the normal water level in the boiler but below a dangerous foam level in the boiler and positioned to be submerged in light 60 water and foam on top of the boiler water before said light water and foam reaches a dangerous level in the boiler, and said tube being arranged to continuously supply steam to the valve until said mouth is submerged, said valve housing having a cylinder therein, a piston slideable in said cylinder, a poppet valve portion on said piston adapted to close the mouth of the tube, a bleeder 65 passageway venting the space in the cylinder above the piston with the atmosphere, a second, larger bleeder passageway also venting said space with the atmosphere, a pilot valve adapted to close said larger passageway, and a thermally operated device carrying said pilot valve, said device adapted to hold the pilot valve against 70 75

the mouth of the larger passageway to close the same when dry steam is discharged through the small passageway but moving said pilot valve away from the large passageway when moisture is entrained with the steam thereby permitting the piston to move in the cylinder for opening the valve.

7. Apparatus for controlling foaming in operating steam boilers which comprises a down pipe 10 extending into the boiler and having the inlet mouth thereof spaced above the normal water level in the boiler but below the steam outlet of the boiler, said mouth of the downpipe positioned to be submerged in light water and foam 15 on top of the boiler water before said light water and foam reaches a dangerous level, a valve closing the other end of the down pipe, and thermally operative means for actuating said valve whenever the mouth of the down pipe is submerged 20 in liquid, or whenever excessive moisture enters said mouth of said down pipe with the steam.

8. Apparatus for controlling foaming in operating steam boilers which comprises a collecting 25 means mounted in the upper portion of a boiler having an inlet above the normal water level in the boiler but below the steam outlet, a down pipe extending into said collecting means and terminating in spaced relation from the bottom 30 thereof, the inlet mouth of said down pipe positioned to be submerged in light water and foam on top of the boiler water before said light water and foam reaches a dangerous level in the boiler, a valve housing mounted on top of the boiler 35 receiving the other end of the down pipe therein, a valve in said housing adapted to close said other end of the down pipe, and thermally operated means for actuating said valve whenever the mouth of the down pipe is submerged in liquid 40 in the collecting means.

9. In an apparatus for controlling foam in an operating steam boiler, a valve adapted to be secured on top of the boiler which comprises a valve housing having an inlet port at the bottom thereof and a discharge port at the side thereof, a cylinder in said valve housing above the inlet port thereof having an open bottom communicating with the discharge port and a top closed by the top of the housing, a valve seat in said 45 inlet port, a piston slidable in said cylinder, a valve on the bottom of said piston adapted to be seated on the valve seat, a passageway through the valve and piston joining the inlet port with the space in the cylinder above the piston, a small bleeder passageway venting said space to 50 the atmosphere, a large bleeder passageway venting said space to the atmosphere, a pilot valve outside of said housing adapted to close the mouth of the large passageway and a Spencer 55 disk supporting said pilot valve whereupon dry steam discharged from the small passageway will heat the disk to hold the pilot valve against the mouth of the large passageway while wet steam or liquid will cool the disk to move the pilot valve away from the mouth of the large 60 passageway and allow the piston to move in the cylinder for opening the valve.

10. In an apparatus for controlling foaming in operating steam boilers, a valve housing adapted 70 to be mounted on top of the boiler, said housing having top and bottom inlet compartments and an intermediate discharge compartment, valve seats joining the inlet compartments with the discharge compartment, valves adapted to be seated on said valve seats, pistons secured to said valves for

said valves for actuating the latter, an open-ended cylinder in said discharge compartment receiving the pistons therein in slidable relation thereto, means defining a passageway joining the space in the cylinder between the pistons 5 with the bottom inlet compartment, means defining a bleeder passageway joining the space in the cylinder between the pistons with the bottom inlet compartment, a float in said bottom inlet compartment, a rod extending from said float 10 through said passageway joining the space in the cylinder between the pistons with the bottom inlet compartment, and a pilot valve on the end of said rod adapted to close the mouth of the bleeder passageway, the arrangement being 15 such that entry of liquid into the bottom inlet compartment will raise the float to move the pilot valve against the mouth of the bleeder passageway and effect an opening of the valves to join the inlet compartments with the discharge 20 compartment.

11. In an apparatus for controlling foam in operating steam boilers, a valve housing adapted to be mounted on top of the boiler, said valve housing defining a float chamber and a discharge 25 chamber above said float chamber, a valve seat joining said chambers, a poppet valve adapted to be seated on said valve seat, a piston secured to said poppet valve, a cylinder in said discharge compartment slidably receiving said piston, means 30 defining a passageway joining the float chamber with the space in the cylinder above the piston, a bleeder passage venting said space with the atmosphere, a rod secured to said float extending through said passageway into the space above 35 the piston, and a pilot valve on the end of said rod adapted to close the vent, the arrangement being such that entry of liquid into said float chamber will raise the float to seat the pilot valve and permit the piston to open the poppet valve 40 for joining the float chamber with the discharge compartment.

12. Apparatus for blowing down a boiler which comprises a thermally operated pilot valve communicating with the boiler and arranged to open 45 when the temperature in the valve drops below a predetermined degree, a blow off valve communicating with the pilot valve and with the interior of the boiler and means in said blow off valve actuated by an opening of the pilot valve 50 to open the blow off valve for blowing down the boiler.

13. In an apparatus for controlling foaming in operating boilers, a valve housing, said housing having top and bottom inlet compartments 55 and a discharge compartment, valve seats joining the inlet compartments with the discharge compartment, valves adapted to be seated on said valve seats, pistons secured to said valves for actuating the latter, a cylinder in said valve 60 housing receiving the pistons in slidable relation thereto, means defining a passageway joining the space in the cylinder between the pistons with the bottom inlet compartment, means defining a bleeder passage joining the space in the 65 cylinder between the pistons with the discharge compartment, a closed float in the bottom inlet compartment, a rod extending from said float through said passageway into the space between the pistons and a pilot valve on the end of said 70 rod adapted to close the mouth of the bleeder passage, the arrangement being such that entry of liquid into the bottom inlet compartment will raise the float to move the pilot valve against the mouth of the bleeder passage and effect an 75

opening of the valves to join the inlet compartments with the discharge compartment.

14. Apparatus for controlling foaming in operating steam boilers which comprises a main valve mounted outside of the boiler having a feed pipe extending therefrom into the boiler, the mouth of said feed pipe being at a level in the boiler above the normal water level but below a dangerous foam level, said mouth of the down pipe positioned to be submerged in light water and foam on top of the boiler water before said light water and foam reaches a dangerous level in the boiler, and said feed pipe being arranged to continuously supply steam to the main valve until the mouth thereof is submerged, means defining a passageway in said main valve for venting steam entering the valve to the atmosphere, a pilot valve cooperating with said passageway and arranged to allow and stop the venting of steam to the atmosphere, and means responsive to liquid entering the main valve through the feed pipe for moving the pilot valve to change the venting of steam and to open the main valve.

15. Apparatus for controlling foaming in operating steam boilers which comprises a valve mounted on top of the boiler, a downpipe extending from the valve into the boiler, the mouth of said downpipe in the boiler being at a level above the normal water level but below the steam outlet of the boiler, said mouth of the downpipe positioned to be submerged in light water and foam on top of the boiler water before said light water and foam reaches a dangerous level in the boiler, and said downpipe being arranged to continuously supply steam to the valve until the mouth thereof is submerged, means defining a bleeder passageway in said valve for venting steam entering the valve to the atmosphere, a pilot valve cooperating with said bleeder passageway and arranged to allow and stop the venting of steam to the atmosphere, and a float responsive to liquid entering the valve on top of the boiler through the downpipe when the mouth of the downpipe is submerged for moving the pilot valve to change the venting of steam to open the valve on top of the boiler.

16. In apparatus for controlling foaming in operating steam boilers including collecting means mounted in the upper portion of a boiler having an inlet above the normal water level in the boiler but below a dangerous foam level, and a main valve mounted outside of the boiler hav-

ing a tube extending into the boiler and terminating near the bottom of the collecting means, the improvements which comprise said tube having an inlet mouth communicating with the bottom portion of said collecting means to receive light water and foam entering the collecting means, said inlet mouth positioned to be submerged in light water and foam received by said collecting means before said light water and foam reaches a dangerous level in the boiler, and said tube being arranged to continuously supply steam to the main valve until the mouth thereof is submerged, means defining a passageway in said main valve for venting steam entering the valve through said tube to the atmosphere, a pilot valve cooperating with said passageway and arranged to allow and stop the venting of steam to the atmosphere, and means responsive to liquid entering the valve through the tube when the mouth of the tube is submerged in liquid in the collecting means for moving the pilot valve to change the venting of steam to the atmosphere whereby said main valve will open only when the level of liquid in the collecting means is above the inlet mouth of the tube.

17. In the method of controlling foaming in operating steam boilers by the use of a blow-off valve, the steps which comprise bleeding a small amount of steam from the boiler into the blow-off valve as long as foam and light water level in the boiler are below a predetermined level, and changing the rate of steam bleeding to said valve by foam and light water exceeding said level to effect an opening of the valve for blowing off foam and light water from the boiler.

18. The method of controlling foaming in operating steam boilers which comprises providing a path for discharge of foam and light water from an operating steam boiler having an inlet at a level above the normal boiler water level but below a dangerous foam level, bleeding steam from the boiler along said path while restricting the flow of steam through said path when the foam and light water level in the boiler is below the inlet to the path, and changing the rate of steam bleeding when the foam and light water lever in the boiler is above the inlet to said path to open said restriction by said change of rate for the discharge of foam and light water from the boiler.
